Attorney

UNITED STATES PATENT OFFICE.

LOUIS A. MACKLANBURG, OF OKLAHOMA CITY, OKLAHOMA.

SASH PLUG.

Application filed May 9, 1923. Serial No. 637,861.

To all whom it may concern:

Be it known that I, LOUIS A. MACKLANBURG, a citizen of the United States, residing at Oklahoma City, in the county of Oklahoma and State of Oklahoma, have invented certain new and useful Improvements in Sash Plugs; and I do hereby declare the following to be a full, clear, and exact description of the invention, such as will enable others skilled in the art to which it appertains to make and use the same.

This invention relates to plugs for window-sash, and more particularly to an improved plug adapted to be attached to the inner face of the bead separating the two sash of the ordinary window adjacent the upper rail of the lower sash.

The invention consists in the novel construction, arrangement and combination of parts as hereinafter more particularly described and claimed.

One sheet of drawings accompanies this specification as part thereof, in which like reference characters indicate similar parts throughout, and in which:

Figure 1 is a perspective view of the improved plug as it may be manufactured to market;

Fig. 2 is a perspective view of the improved plug shaped for use;

Fig. 3 is a front elevation of the plug applied, part of the sash being broken away;

Fig. 4 is a horizontal cross sectional view taken through the upper rail of the lower sash.

In accordance with the present invention suitable strips 1 of sheet metal of a generally rectangular form are provided upon one face with a block 4 of felt, fibre, or the like.

The end edges of the metal strip 1 may be up-turned slightly as at 2-2, and the strip is so proportioned with respect to the felt block 4 as to leave its ends exposed, which will be provided with suitable holes 3 through which the attaching nails or screws may be driven.

The plugs may, of course, be manufactured in strips or in individual units as illustrated, and the felt plugs may be of rectangular form as illustrated in Figure 1, or they may be preliminarily shaped with a convex upper face 5, as illustrated in Fig. 2.

Where the plug is provided with the felt in rectangular form, the artisan applying it will be expected to shave the felt block to a convex form as illustrated in Fig. 2 preliminary to applying the device.

The plug is applied by flexing the metal backing 1 toward the felt part 4 as illustrated in Fig. 3, so that the convex face 5 of the felt part assumes a straight line, thus compressing the felt intermediate the bead 7 of the window jamb and the metal backing 1 of the plug, leaving the metal backing exposed to furnish a sliding contact with the rail of the sash.

In practice the plugs will be made of a length slightly greater than the width of the upper rail of the sash, and positioned intermediate the rail and the bead with the sash in its lowered or closed position.

Having thus fully described my invention, what I claim as new and desire to secure by Letters Patent of the United States is,

1. An article of manufacture comprising a piece of flat flexible sheet metal of substantially rectangular form having a block of felt secured to one face, this felt having its outer face of convex form tapering toward the ends of the metal strip.

2. In association with window sash and frame, a plug comprising a flexible sheet metal part affixed to felt having a convex outer metal part, said back flexed toward the felt until the outer convexed face of the felt coincides with the surface of the part of the frame against which it is applied, the said metal part constituting a convex slide surface for the sash.

In testimony whereof I affix my signature.

LOUIS A. MACKLANBURG.
